UNITED STATES PATENT OFFICE

2,007,943

THERMIONIC DEVICE

Chester H. Braselton, New York, N. Y., assignor
to Sirian Lamp Company, Newark, N. J., a corporation of Delaware

Application October 21, 1930, Serial No. 490,126
Renewed April 18, 1935

5 Claims. (Cl. 250—27.5)

This invention relates to thermionic devices used as rectifiers, amplifiers, or detectors in electrical circuits.

One of the objects of the invention is to provide a cathode for a thermionic device which is simple and easily constructed.

Another object of the invention is to provide a cathode for a thermionic device which may have a greater resistance so that the cathode 10 may be energized by higher voltages if desired.

Another object of the invention is to provide a simple method of rendering a cathode electron emitting.

Other objects of the invention and objects 15 relating particularly to the construction and assembly of the various parts will be apparent as the description of the invention proceeds.

One embodiment of the invention has been illustrated in the accompanying drawings in 20 which:

Fig. 1 is a front elevational view of a thermionic device partly in section and with one-half of the anode removed to show the interior parts;

Fig. 2 is a sectional side elevational view of the 25 elements of the device shown in Fig. 1;

Fig. 3 is a sectional front view of a heater type thermionic tube embodying the invention; and

Fig. 4 is a sectional side view of the elements 30 of Fig. 3;

Fig. 5 is an enlarged view of one end of the heater element.

Referring now more specifically to Figs. 1 and 35 2 of the drawings the invention is shown in a thermionic device comprising an envelope 10 of glass or other desirable material sealed in the usual manner to a press 11 which supports the various elements of the device. The elements comprise an anode 12, a grid 13, and a cathode 14.

40 The anode 12 may be formed of two plates each having a semi-cylindrical portion 15 with a flange 16 at each side thereof extending radially therefrom. The flanges 16 may be provided with grooves 17 adjacent their outer edges to 45 receive a pair of support rods 18 which may extend parallel to each other and may be bent inwardly and downwardly and to be sealed in the press 11. When the two plates for the anode are assembled upon the support rods they may be 50 welded to the support rods so that a cylindrical anode is formed with a flange at each side thereof attached to one of the support rods 18.

55 The helical grid 13 may be supported upon a support rod 19 as by welding thereto and this rod may be welded to a support rod 20 which is

sealed in the press 11 while the upper end may be welded to an angular rod 21 which may extend backwardly and be bent downwardly to be sealed in a glass bead 22. The upper ends of the support rods 18 may also be bent backwardly and downwardly and may be sealed in the bead 22.

5 The cathode 14 positioned inside of the grid 13 may comprise a core 23 of electron emitting material which may be any of the materials commonly used for that purpose such as the oxides 10 of the alkali earth metal group or mixtures of such oxides held together with a suitable binder.

Around the core 23 may be wound a core 24 of 15 resistance wire such as tungsten, molybdenum, tantalum, or nichrome, and the core may be held inside of the coil by slightly deforming the coil at each end of the core. The wire may be wound around the core or the coil may be formed first and the coil slipped inside of it. In either case 20 the core is in contact with the turns of the coil and helps to hold the coil to prevent the turns from touching each other. The lower end of the coil may be attached to a support rod 25 which 25 may be sealed in the press 11 and the upper end of the coil may be connected to the support rod 26 which may extend rearwardly and be bent downwardly parallel to the anode and inwardly again beneath the anode and downwardly again to the press 11 in which it may also be sealed. Thus the support rods 25 and 26 form the filament 30 or cathode leads for the device.

A short angular connector 27 may be sealed in the bead 22 and may be welded to the support rod 26 to anchor the bead with respect to the support rod thereby holding the upper ends of 35 the other elements rigidly in position.

Leading-in wires 21, 28, 29, and 30 may be connected to the support rods 18, 20, 26, and 25 which may in turn be connected to terminals 31, 32, 33, and 34 mounted on the base 35 which may be 40 attached in the usual manner as by cementing to the envelope 10.

If desired the envelope 10 may be exhausted to 45 operate the device in a vacuum or it may be desirable to add a pure inert gas with a pressure in the neighborhood of 200 mm. of mercury. Any inert gas may be used but I prefer the monatomic gases such as argon, neon, helium, krypton, or

xenon, or mixtures of these gases, or if desired certain metal vapors may be mixed with the gas 50 or gases to increase the conductivity of the device. These metal vapors may be the vapors of mercury, rubidium, caesium, calcium, or cadmium, and they may be introduced into the bulb by providing 55 a salt such as a chloride of the desired metal

in a container 36 made of pressed metal with a small piece of magnesium. When the container 36 is heated as by external bombardment after the envelope is sealed off the magnesium will combine with the chloride of the desired metal liberating the free metal and forming magnesium chloride. The free metal will condense on the walls of the envelope to be evaporated again when the envelope is heated in use. The container 10 36 may be attached by means of a support wire 37 to one of the support rods, as the rod 18, as indicated.

In Figs. 3 and 4 the invention is shown in connection with a heater type tube. In this construction a coil 38 of resistance wire similar to the coil in the other figures is provided with a core 39 of electron emitting material similar to that already described. The coil may be mounted at its lower end upon a support rod 40 which may be sealed 20 in the press 41 and at its upper end upon a support rod 42 which may extend backwardly, downwardly, and inwardly again to be sealed in the press 41. A cylindrical cathode 43 may be provided surrounding the coil 38 but spaced therefrom and the cathode may be supported at its lower end by means of a strap 44 extending around the cathode and welded to a support rod 45 sealed in the press 41. The upper end of the cathode may be supported by means of a strap 30 46 which extends around the end and may be welded to a short support rod 47 sealed in a bead 48 similar to the bead described in connection with the previous figures. The cathode may be coated as indicated in Fig. 4 with electron emitting material 49. The glass bead 48 may be rigidly held in position by a short angular connector 50 which may be sealed in the bead and welded to the support rod 42.

A helical grid 51 may be provided similar to 40 the grid already described and it may be held in position by a support rod 52 which may be welded or otherwise attached at its lower end to a short support rod 53 which is sealed in the press 41 and at its upper end to an angular support rod 45 which may be sealed in the bead 48.

An anode 55 similar to the anode described in connection with Figs. 1 and 2 may surround the grid 51 and may be supported upon two support rods 56 which are sealed in the press 41 and having their upper ends welded to two angular support rods 57 which may be sealed in the bead 48.

Leading-in wires 58, 59, 60, 61, and 62 may be connected respectively to support rods 56, 53, 40, 42, and 45 and the tube is adapted to have a five terminal base (not shown) with a separate terminal for the cathode connection.

In this device the cylindrical cathode is heated to electron emitting temperature by radiation from the coil of filament wire and also by electron bombardment from the core of emitting material. The tube may be operated in a vacuum or may be provided with a gas as described in connection with Figs. 1 and 2.

In preparing either of the constructions shown 65 and described the following process as described in my copending application Serial No. 459,048, filed June 3, 1930, is recommended:

With the elements all mounted in the envelope as shown the envelope may be connected to an 70 exhaust pump and an oven placed over it in the usual manner to raise the temperature to between 350 to 400° C. A current may be run through the filament at this time to raise the temperature thereof to approximately 600° C. to drive out the 75 occluded gases in the filament and other parts

of the envelope. When no more gases appear in the envelope as is evidenced by the lack of fluorescence when high tension current is directed against the envelope from an induction coil the filament current may be increased to approximately 800° C. This drives out the binder from the electron emitting material and other occluded gases. When no more gases appear in the envelope the oven may be raised and the filament current increased for a moment to raise the temperature to less than 1200° C., the vacuum pump being connected all this time to remove the gases as they are driven off.

When the envelope is again free of gases the 15 vacuum pump may be shut off, the current turned off, and a slight amount of an inert gas, such as neon at a pressure of about 1/2 mm. of mercury, may be admitted into the bulb and the filament current turned on again and gradually increased. Spots of localized discharge will then appear having 20 a reddish color and will gradually spread until the discharge fills the entire bulb. This appears to activate the electron emitting material and should be carried on until the discharge completely fills the bulb which should take less than 25 ten minutes. If white discharge spots appear on the filament or other parts of the device it is an indication that all of the gases or vapors have not been removed and the exhaust pump should again be connected and the tube exhausted and 30 the whole process of activation repeated.

When the activation process is completed the filament current may be increased for a moment to raise the temperature to about 1400° C. and then the exhaust pump connected again to remove the gases. A high vacuum of about .5 micron is preferably obtained at this time after which the pump may be shut off, the filament current turned off, and the bulb may be sealed off either in the evacuated condition or after admitting the desired gases. I have found that about 50 mm. of neon and 150 mm. of argon when these gases are chemically pure give good results although other gases as mentioned above and metal vapors may be used if desired.

Many modifications of the invention may be resorted to such as changing the shape and position of the electrodes and the elimination of the grid or the addition of more grids, and I do not therefore desire to limit myself to what has 50 been shown and described except as such limitations occur in the appended claims.

What I desire to claim and secure by Letters Patent is:

1. In a thermionic device an anode, a cathode 55 spaced from said anode, a heater for said cathode comprising a coil of filamentary resistance wire spaced from said cathode, and a core of electron emitting material within said coil.

2. In a thermionic device an anode, a cathode 60 spaced from said anode, a heater for said cathode comprising a coil of filamentary resistance wire spaced from said cathode, a core of electron emitting material within said coil and in surface contact therewith, and an ionizable gas surrounding 65 said anode, coil, and core.

3. In a thermionic device an anode, a tubular cathode, and a heater for said cathode comprising a coil of filamentary resistance wire and a core of electron emitting material within said coil and 70 in surface contact therewith.

4. In a thermionic device an anode, a cathode spaced from said anode, a heater for said cathode comprising a coil of filamentary resistance wire spaced therefrom, a core of electron emitting ma- 75

terial within said coil and in surface contact therewith, and a mixture of neon and argon gases surrounding said anode, cathode, and heater.

5. In a thermionic device an anode, a cathode spaced from said anode, a heater for said cathode comprising a coil of filamentary resistance wire spaced therefrom, a core of electron emitting ma-

terial within said coil and in surface contact therewith, and a mixture of neon and argon gases surrounding said anode, cathode and heater, said gases having a pressure of approximately 200 mm. of mercury.

CHESTER H. BRASELTON.
